VOLTAGE REGULATOR

August Toelle and Corado R. Salet, Detroit,
Mich., assignors to Ford Motor Company, Dear-
born, Mich., a corporation of Delaware

Application January 14, 1944, Serial No. 518,224

2 Claims. (Cl. 201—48)

This invention relates to an apparatus for a contact breaker used in a voltage regulator for controlling the flow of electricity in electrical equipment in motor vehicles and the like.

In vehicle electrical installations, a voltage regulating device is provided between the generator and battery which is operative as a cutout on the production of certain predetermined voltages. The resultant vibrating action of the voltage regulator necessarily causes some arcing between its switch contacts and in the normal course of operation, these contacts will be eroded or pitted and their efficiency will be decreased. A number of ways have been suggested for increasing the life of the regulator contacts, including improvements both in the materials from which contacts are made and the use of auxiliary devices which will reduce the spark potential effective when the circuit is broken. Following the first course, a number of contact alloys have been developed which have been found highly resistant. However, due to the shortages arising from wartime demands, many of the alloying elements are no longer available and it is necessary to use substitutes which do not have the inherent resistance to erosion through arcing that the other metals possessed.

Since it is no longer possible to obtain these highly resistant alloys, recourse must be had to auxiliary means which will reduce the arcing effect and thereby render the available contact alloys at least as efficient and durable as those previously used. The present invention contemplates an extremely simple method of reducing the arcing effect between the contacts of a voltage regulator and doing it with apparatus which is simple and easy to construct, entirely automatic in operation and certainly as durable and efficient as the prior voltage regulator construction. An advantage of the present invention is that means are provided to subdivide—as it were—the breaking of the contact and to govern the resistance of the circuit over these subdivisions intermediate the breaking of contact at the regulator; and proportioning this resistance so that the arcing potential over any one subdivision is materially reduced. It thus follows that the life of the contacts is proportionately increased and their durability enhanced without any decrease of electrical efficiency. The outstanding result is a net gain in contact life without necessitating the use of the rarer alloying metals, which are intrinsically better but which are no longer available.

With these and other objects in view, the in-

vention consists in the arrangement, construction and combination of the various parts of the improved device, as described in the specification, claimed in the claims, and illustrated in the accompanying drawing, in which:

Figures 1, 2, 3 and 4 are diagrammatic representations of successive stages in the operation of a voltage generator employing this invention.

Figure 5 is an elevation of the particular voltage regulator unit.

Referring to Figure 5, the regulator 10 comprises an L-shaped frame 11 on which is mounted a coil 12 wound on the core 13 and an armature 14 hingedly supported by the leaf spring 15. A moving contact point 16 is mounted on the lower arm 17 of the armature 14 and a fixed contact point 18 is insulatedly supported on an extension 9 secured to the frame 11. So far, it will be recognized that the construction is entirely conventional.

The novelty in the present regulator is the provision of a plurality, in this case two, intervening contact points 19 and 20 arranged between the moving and fixed contact points 16 and 18. Each of the intervening contact points comprises a flexible or resilient spring shank 21 mounted between the insulating blocks 22 intermediate the spacer 23 and the extension 9 attached to the frame 11. Each shank 21 has a double faced contact head 24 substantially in alignment with the contact points 16 and 18. It is thus apparent that a series of contacts is provided and that when the circuit is closed, points 16, 18, 19 and 20 are all in contact and that provision may be made for opening the circuit by successively breaking contact between adjacent contact points.

Reference is now made to Figures 1 through 4 illustrating the electrical connections in the circuit with the several components of the regulator. Similar reference characters indicate identical elements as described with respect to Figure 5 and, in addition, the regulator is shown interposed in a typical automotive electrical circuit in which 25 is the battery, 26 the generator and 27 the ground. However, the structure of the regulator is much simplified and those of its elements which are not germane to the present invention such as the compensating means and the like are not shown. It will be noted that a resistance 28 is connected across the principal contacts 16 and 18, and that this resistance is further tapped by leads to the intervening contact points 19 and 20 to form, in reality, three separate resistances 29, 30 and 31 connected in

series. In Figure 1, the four contacts are shown together and the circuit is closed directly through them and no current flows through the combined resistance 28. Figure 2 shows the first of the successive steps by which the vibrator opens and in it the armature 14 is being attracted downwardly to the coil 12 and the contact between points 18 and 20 has been broken while that at 20, 19 and 16 is maintained. The current now flows through the first of the separate resistances, portion 29, which is shown in heavier line and thence through 20, 19 and 16. Figure 3 shows the next step in which the descent of the armature continues and in which contact 20 has moved away from contact 19. However, contacts 19 and 16 remain in engagement and the current flows through two of the separate resistances, portions 29 and 30, which are, as stated above, arranged in series and thence through 16 and 19. Figure 4 shows the final stage in the descent of the armature 14 in which all of the contact points are disassociated and in which any current across the contacts must flow through the combined resistance 28 comprising all three of the separate resistances 29, 30 and 31 connected in series. This, of course, reduces the effective flux of the coil 12 and the spring 15 returns the armature to its uppermost position effecting successive contact between the four contact points until the condition shown in 5 is resumed and the vibratory cycle can be repeated. As a practical matter, the combined resistance 28 should aggregate about 100 ohms for a 24 volt system and 50 ohms for 12 volts and this may be divided in as many increments as desired.

It will be understood that this cycle is repeated continuously and in itself is practically instantaneous. It is further recognized that in the conventional construction, the breaking of contact between the points is inevitably accompanied by some arcing, which, in time, must have a deleterious effect on the contacts and will destroy their electrical efficiency. It is believed clear from the description of the device how the construction utilized cuts down this arcing to a point at which it is no longer objectionable and permits the use of metals for the contact points of lesser durability. In short, rather than concentrating the arcing at any one pair of contact points, the operation is conducted successively and resistances are interposed between successive contacts so that the arcing potential between any two is reduced to a point at which no damage is caused.

Following the first four figures in order, it is clear that the interposition of the successive resistances between the opening contact points reduces the potential to a point at which no damage will occur. To effect this sequence, it is essential that the contacts open in precisely the order shown. Therefore, means must be provided to prevent, for example, contact 16 opening from contact 19 initially as the armature moves downwardly, or contact 19 opening from contact 20. To obtain this sequence, it is essential that the spring 15 and the spring shanks 21 of the contact points 19 and 20 be carefully equated so that as the armature moves downwardly, the initial break will occur between contacts 20 and 18 and that the resiliency of spring shank 21 of contact 20 be sufficient to maintain connections between contacts 20, 19 and 16. Similarly, as the armature continues its course, contact 20 will come to rest and thereafter the resiliency in the shank 21 of contact 19 must be sufficient to keep contact 19 in connection with

contact 16 until the armature has moved to a position at which these two contacts would normally break. Therefore, it is apparent that there may be a graduated resiliency between the three springs to effect the desired sequence of operation and overcome the inherent inertia of the contacts which otherwise would tend, at worst, to permit opening in the inverse order.

It is believed that operation of the advantages in the present construction will be clear from the foregoing. The electrical connections have not been indicated in Figure 5 or shown in full in the other figures as they will be clear to those skilled in the art since the circuit and the breaker construction are conventional apart from the multi-contact feature described. The successive introduction of increments of resistance will reduce the spark potential and reduce the amount so that it can no longer be deleterious to the individual contacts. Thus, although the number of contact surfaces is multiplied, the life and efficiency of the device, as a whole, is increased many times over those employing but a single pair of contacts; and permits, as an alternative, the use of less suitable alloy materials in the contact points themselves without a sacrifice in operating efficiency.

Some changes may be made in the arrangement, construction and combination of the various parts of the improved construction without departing from the spirit of the invention, and it is the intention to cover by the claims such changes as may be reasonably included within the scope thereof.

35 The invention claimed is:

1. In a voltage regulator, an L-shaped base, an electromagnet fixedly mounted on one leg of said base and spaced from the other leg thereof, an L-shaped movable armature pivotally supported at the end of said other leg of said base, one leg of said armature overlying and actuated by said electromagnet, a fixed contact supported on said base between said other leg thereof and said electromagnet, a cooperating contact on the other leg of said armature positioned between said other leg of said base and said fixed contact, a plurality of auxiliary spring leaf supported contacts between said fixed contact and said cooperating contact and successively aligned therewith to form a series of interengaging contacts adapted to permit electrical connection therethrough when said armature is remote from said electromagnet, substantially equal increments of resistance connected in series between each of said contacts, and means effective on the moving of said cooperating contact as said armature approaches said electromagnet to break initially the connection between said fixed contact and the adjacent auxiliary contact before breaking 60 the connection between said cooperating contact and its adjacent auxiliary contact.

2. In a voltage regulator, a base, an electromagnet fixedly mounted on said base, a movable armature pivotally supported on said base cooperating with and actuated by said electromagnet, a fixed contact on said base, a cooperating contact on said armature, a plurality of auxiliary contacts mounted on leaf springs insulatedly supported on said fixed contact between said fixed contact and said cooperating contact and successively aligned therewith, said auxiliary contacts having opposite contact faces and adapted to engage an adjacent auxiliary contact or said fixed or said cooperating contact as the case may 75 be to form a series of contacts affording a direct

connection therethrough and to open successively and provide an alternative connection through increments of resistance connected in series therebetween, said leaf springs supporting said auxiliary contacts being so proportioned as to resiliency that on movement of said cooperating contact in response to movement of said armature from its remote position, the connection between said fixed contact and its immediately ad-

5 jacent auxiliary contact will be broken initially, and breaking of the connection between successive adjacent auxiliary contacts will follow, and the breaking of connection between said cooperating contact and its immediately adjacent auxiliary contact will occur in that order.

AUGUST TOELLE,
CORADO R. SALET.
